by Crosby & Gregory,

UNITED STATES PATENT OFFICE.

HORACE WYMAN, OF WORCESTER, MASSACHUSETTS.

VICE.

SPECIFICATION forming part of Letters Patent No. 340,930, dated April 27, 1886.

Application filed August 24, 1885. Serial No. 175,182. (No model.)

To all whom it may concern:

Be it known that I, HORACE WYMAN, of Worcester, county of Worcester, State of Massachusetts, have invented an Improvement in Bench-Vises, of which the following description, in connection with the accompanying drawings, is a specification, like letters on the drawings representing like parts.

This invention has for its object to construct a bench-vise which may be readily and quickly operated to firmly grip material of various thicknesses.

The invention relates to that class of vise which comprises a fixed jaw provided on its under side with a rack-bar and a movable jaw sliding with relation to the fixed jaw and carrying a shaft provided with a worm, combined with a block engaged by the said worm, and having teeth upon its upper side to engage with the teeth of the rack-bar, and inclined bearing-faces on its under side to co-operate with inclined bearing-shoulders preferably made integral with the movable jaw, and acting to cause the said block as it is moved by the rotation of the worm to rise and fall upon the inclined bearing-shoulders, to thus engage or disengage the rack-bar.

In my invention the block engages stationary inclines, and the fixed jaw is provided longitudinally upon its under side with flanges, which serve to support the movable jaw with its engaging mechanism, said movable jaw being provided with corresponding flanges to move upon the flanges of the fixed jaw and permit the movable jaw to be drawn back and forth at will.

Figure 1 is a longitudinal section of a bench-vise constructed in accordance with this invention, the portion of the frame-work or bench to which the same is attached being shown in dotted lines; Fig. 2, a cross-section of the vise, taken on the dotted line $x-x$, Fig. 1; and Figs. 3 and 4, details of the ratchet-toothed block to be referred to.

The fixed jaw A, secured to any suitable frame-work or bench, A', is provided on its under side with a rack-bar, B. The fixed jaw A is provided on its under side with in-turned flanges a, (see Fig. 2,) which support and permit an easy longitudinal movement thereon of the movable jaw C, which is pro-

vided with corresponding outwardly-turned flanges a'. The movable jaw C is provided with a biting-face, c, which co-operates with the biting-face a² of the fixed jaw, to grip any material which may be placed between them. The movable jaw C carries an oscillating shaft, e, passing lengthwise of the same, and mounted in suitable bearings at each end, said shaft being oscillated by the hand-lever e', secured to the forward end thereof to be readily accessible to the operator. The shaft e has mounted upon it at or near its rear end a worm, e², which engages the block f, which latter is provided on its upper side with teeth adapted to engage the teeth of the rack-bar B of the fixed jaw A. The block is moved back and forth by the rotation or oscillation of the worm e², and is provided upon its lower surface with inclined or beveled faces f', preferably at each end, which rest upon inclined bearing-shoulders f², preferably made integral with movable jaw C, so that as the said ratchet-toothed block is moved back and forth by the worm it will rise and fall upon the inclined bearing-shoulders.

The block f is preferably composed of one piece, as shown in Fig. 4; but it is obvious that the same may be composed of two pieces, one of which, containing the screw-threaded portion to engage the worm, being fitted into the ratchet-toothed portion of the block.

To grip any material which it may be desired to place between the jaws, the operator grasps the hand-lever e³ in the position shown in Fig. 1, and draws the movable jaw C toward or from the jaw A, according to the thickness of the material. The material is then placed between the jaws, the jaw C forced against it, and the hand-lever e' is turned half of a revolution, which movement causes the block f to move forward upon the inclined bearing-shoulders f² and the ratchet-teeth of the said block f to engage the teeth of the rack-bar B. It will be seen that the block f is provided with four bearing-faces, so as to secure the utmost strength.

In order to have the teeth of the block f engage the rack properly, the under side of the inclined faces f' are adapted to slide over the top of the inclined blocks f² when the block is fully raised, so that the teeth may be fully

engaged with each other in any position of the jaws. When the teeth of the rack are thus fully interlocked, further movement of the shaft *e* tends to draw the jaws closer together, firmly gripping anything that is interposed between the jaws.

I do not broadly claim a vise having a fixed jaw provided on its under side with a rack-bar, and a movable jaw sliding upon said fixed jaw, and carrying a screw-shaft which operates a toothed block to engage said rack-bar to hold the movable jaw in desired position, said block having inclined shoulders co-operating with inclined lugs or bearing-surfaces on or moved by the screw-shaft to elevate said block when moved by the shaft into engagement with the rack-bar.

I claim—

The within-described vise, consisting of the stationary member *A*, having a rack-bar, *B*, 20 and supporting-ways for the movable member, the movable member *C*, supported by and movable on the said stationary member, and the worm-shaft *e* and toothed block *f*, operated longitudinally by the oscillation of said shaft, 25 and having the inclines *f'*, engaging the stationary inclines *f''*, to raise and lower said block as it is moved longitudinally by the shaft, substantially as set forth.

In testimony whereof I have signed my name 30 to this specification in the presence of two subscribing witnesses.

HORACE WYMAN.
